Lyman Whittle of Vienna Maine
Letters Patent.

The Schedule referred to in these Letters Patent and making part of the same containing a description in the words of the said Lyman Whittle himself of his improvement in the Chair.

To all to whom these Presents shall come, I the subscriber, Lyman Whittle of Vienna in the County of Kennebec and State of Maine have made and do make and seal this 10th day of February in the year of our Lord 1836, a full and true description of the construction and operation of said Chair, invented and improved by me. First. The chair which receives the name is the ordinary round chair of such size as may be desired. To this chair a frame is attached as follows. 4 pieces of wood $1\frac{1}{2}$ by $1\frac{1}{2}$ inch square, and 4 feet 6 inches long are united at one end like the letter A (without the cross) Midway of these pieces a piece of wood $1\frac{1}{2}$ inch by 2 inches and 3 feet long, crosses the two pieces (by being let in so as to have them even on both sides) which constitutes one side. Another side is made like unto it, and the two sides are united together by 2 pieces of wood of the size of the other cross pieces at the foot of the piece, (like the letter A) and also by 2 pieces across from the ends of the cross pieces on the side - which makes the frame to consist of six pieces. The last named cross pieces which unites the two sides being 15 inches long, and the pieces on the side being 3 feet long gives an open space of 3 feet one way (that is, between the sides) and fifteen inches from one side to the other. Within this space the chair is suspended by being attached to two upright slats $1\frac{1}{2}$ inch wide $1\frac{1}{2}$ inch thick. The slats are fastened at the upper end to a roller which rolls over on the upper end or top of the sides of the frame, in such a manner as to permit the roller to turn free and easy. Within the chair an upright shaft is set on a pivot (in the center) 3 feet long (the chair say - being 22 inches deep) and on this shaft which should be of convenient size, above the top of the chair is placed a wheel, say 3 inches diameter having 10 or 12 cogs, in it (as more or less, as may be desired) the upper end of the shaft is kept in a central position by a cross piece from one slot to the other into which the top of the shaft enters. A pair of bars by 3 inches wide $1\frac{1}{2}$ inch thick and 3 feet long rest on the cross pieces when

annual, the sides of the frame (in the centre) from the middle of the pinion (or central cogwheel) in a circle comprising the wheel of the chain is set say 25 eggs - which are made with the egg iron on the side or on the shaft so that when the chain drives, like the pendulum of a clock it will give motion to the shaft forward & back again. At the lower end of the shaft within the chain are breakers or lades, in such number & size as may be thought necessary to give sufficient motion to the cream. The chain is run round conveniently by a small rod say 16 feet long attached to the bottom of the chain. A Patent is claimed for the manner of producing the motion to the cream by the action of the roller and eggs.
